UNITED STATES PATENT OFFICE.

WILLYE F. DISHON, OF STANFORD, KENTUCKY.

AUTOMATIC BLEEDING MECHANISM FOR AIR LINES OF TRAIN AIR-BRAKE MECHANISM.

Application filed May 2, 1927. Serial No. 188,215.

This invention relates to new and useful improvements in automatic air braking systems for trains and has more particular reference to a train line bleeding device operable automatically by a car jumping its rails for braking the train and materially lessening the liability of one or all of the cars from turning over.

In carrying out my invention, there is provided means normally located slightly above one of the track rails and operable to open a valve in the train line for causing the bleeding of the air from the auxiliary reservoir which will automatically apply the brakes.

The primary object of this invention is to provide a device of this character that may be associated with air brake systems without in any manner changing the construction of the system or affecting the proper operation of the system, as long as the cars remain on the trackway.

A further and important object is to provide such a device that may be readily and without great expenditure installed in all types of cars now in use equipped with air brake devices and this without the necessity of jacking up the cars, or without tying the same up for any considerable length of time.

With the foregoing and other objects in view, it is obvious that other advantages of the invention will become more readily apparent from the following description when taken in connection with the drawings.

In the accompanying drawing forming part of this application:—

Figure 1 is a fragmentary side elevation of a car on a trackway equipped with an air brake mechanism and further equipped with an automatic lead device for the train line constructed in accordance with the present invention.

Figure 2 is a rear elevation of the device per se.

Fig. 3 is a detail longitudinal section thereof, and taken substantially on line 3—3 of Fig. 2.

Fig. 4 is an enlarged fragmentary longitudinal section taken substantially from the line 4—4 of Fig. 2, more clearly disclosing the valve unit of the device.

Now having particular reference to the drawing, my novel train line bleeding device consists of a plunger housing 5 constructed from a pair of sections 6—6 ar-

ranged in abutting relation and being tightly joined by a plurality of bolt and nut connections 7 arranged in spaced relation throughout the length thereof. The opposed faces of these sections 6—6 adjacent the outer edge thereof, are channeled to provide a plunger bore 8 extending throughout the entire length thereof.

Longitudinally slidably within the bore 8 is an elongated plunger 9, the lower end 65 of which normally projects considerably beyond the lower end of the housing and is provided with a right angular rail engaging foot 10 for a purpose hereinafter more fully described.

One section 6 of the housing 5 is formed at one end with a right angular extension to provide a bracket 11 which bracket cooperates with the adjacent section 6 of the housing to facilitate the attachment of the same 75 in a rigid manner to the wheel truck of a car A by an L-shaped bracket 12, see Fig. 1.

When attached in the manner as indicated in Fig. 1, the lower end of the housing 5 is considerably above the rail B while the 80 foot 10 upon the lower end of the plunger 9 is normally slightly above the rail B and at right angles thereto so that when the car jumps the track, said foot will encounter the rail to cause the upward movement of the 85 plunger within the housing 5 for a purpose shortly to be described.

The upper end of this plunger 9 is preferably formed with a threaded extension 13 onto which is threaded the lower end of a 90 metallic hub 14 arranged within the upper end of the housing bore 5 for normally maintaining the upper end of the bore closed, but to permit the lubricant to be deposited therein when the cap is removed.

One section 6 of the housing 5 is formed adjacent its upper end with a hollow circular enlargement 15, that cooperates with an arcuate depression 16 at the inner face of the other housing section 6 to provide a 100 casing 17 for a rounded valve core 18, see Fig. 4. This core is arranged upon a valve stem 19 that is equipped with a small rack gear 20 directly in front of a plunger 9 movable within the housing 5, the upper end 105 of the plunger being provided with rack teeth 21 having mesh with the teeth of said rack gear, as clearly indicated in Fig. 3.

Leading into an opening in the upper end of the forward section 6 of the plunger 110

housing 5 is a nipple 22 that has communication with the train line C of the air brake mechanism, by reason of a flexible hose 23. The valve casing forming portion 15 of the opposite housing section 6 is formed with an air exhaust nipple 24 which nipple is placed in communication with the train line C when the valve core 18 is rotated in a counter-clockwise direction by the upward movement of the plunger 9 when the switch 10 of the same engages the rail B should the car jump the track.

This will obviously bleed the auxiliary reservoir D of the car brake mechanism resulting in the application of the brake.

To maintain the plunger 9 in upwardly directed position to prevent the closing of the valve the plunger 9 is formed with longitudinally extending ratchet teeth 25, while the adjacent section 6 of the plunger housing 5 is equipped with a spring pressed dog 26 for engagement with said teeth, see Fig. 3.

This dog is formed with a pin 27 that extends through an opening outwardly, in the housing section, so that the same may be swung out of engagement with the ratchet teeth, to permit the lowering of the plunger.

It will thus be seen that I have provided a highly novel, simple and efficiently operating automatic bleeding device for the train lines of air brake mechanisms installed and associated with train cars that is well adapted for all of the purposes heretofore designed, and even though I have herein shown and described the invention as consisting of certain detail structural elements, it is nevertheless to be understood that some changes may be made therein without affecting the spirit and scope of the appended claims.

Having thus described my invention, what I claim as new is:

1. In an automatic bleeding device for the air brake system of a train of cars, a housing constructed of a pair of elongated plates, one of said plates adapted for attachment to a car; said plates being formed with inlet and outlet openings in communication with the air brake system, a valve member operable within said housing for closing said inlet and outlet opening, a plunger slidable between the said plates, the upper end portion of said plunger being associated with the valve in a manner whereby the same will actuate the valve when moved inwardly within the housing.

2. In an automatic bleeding device for the air brake system of a train of cars, a housing constructed of a pair of elongated plates, one of said plates adapted for attachment to a car, said plates being formed with inlet and outlet openings in communication with the air brake system, a valve member operable within said housing for closing said inlet and outlet opening, a plunger slidable between the said plates, the upper end portion of said plunger being associated with the valve in a manner whereby the same will actuate the valve when moved inwardly within the housing, and means for retaining said plunger in a retracted position within the housing.

3. In an automatic bleeding device for the air brake system of a train of cars, a housing constructed of a pair of plates secured together, the upper end of one of said plates being provided with a valve casing, the complementary plate being secured to the car, a valve member operable within said casing and projecting between the plates, a plunger slidable between the plates, cooperative means between the valve and the plunger, whereby the valve will be actuated for releasing the air in the brake system, the lower end of said plunger adapted to depend below the lower end of the housing, and means for retaining the plunger in a retracted position after having been moved within the housing.

4. In an automatic bleeding device for the air brake system of a train of cars, a housing constructed of a pair of plates secured together, the upper end of one of said plates being provided with a valve casing, the complementary plate being secured to the car, a valve member operable within said casing, and projecting between the plates, a plunger slidable between the plates, cooperative means between the valve and the plunger, whereby the valve will be actuated for releasing the air in the brake system, the lower end of said plunger adapted to depend below the lower end of the housing, means for retaining the plunger in a retracted position after having been moved within the housing, said means consisting in forming the plunger with a rack of teeth, and a pawl arranged within said housing for engagement with the rack for retaining the plunger in a retracted position.

In testimony whereof I affix my signature.
WILLYE F. DISHON.
